UNITED STATES PATENT OFFICE.

HOWARD H. TALBOT, OF WOOSTER, OHIO, ASSIGNOR, BY MESNE ASSIGNMENTS, TO MACKINTOSH-HEMPHILL COMPANY, OF PITTSBURGH, PENNSYLVANIA, A CORPORATION OF PENNSYLVANIA.

COILING MACHINE.

Application filed June 21, 1921, Serial No. 479,210. Renewed February 16, 1924.

To all whom it may concern:

Be it known that I, HOWARD H. TALBOT, a citizen of the United States, residing at Wooster, in the county of Wayne and State 5 of Ohio, have invented certain new and useful Improvements in Coiling Machines, of which the following is a specification.

My invention relates to the art of reeling or coiling metal strips, and consists of a machine adapted to coil strip steel as it is delivered from the mill. It has in view to provide a machine of this type capable of winding the strip around a gripping core, upon an edge supporting table, capable of lowering 15 adjustment and separation of the core by the operator on completion of the operation, for removal of the coil, with various other features of construction and operation, as hereinafter more fully described.

20 Referring to the drawings showing one preferred embodiment of the invention:

Fig. 1 is a plan view showing the apparatus installed in connection with a mill and delivery table;

25 Fig. 2 is an enlarged plan view of the coiling machine, partly in section;

Fig. 3 is a side elevation, partly in section;

30 Fig. 4 is a transverse section on the line IV-IV of Fig. 3;

Fig. 5 is a similar partial section showing the core fingers lowered for removal of the coil;

35 Fig. 6 is a sectional detail view showing the mounting of one of the core fingers.

Referring to Fig. 1, A represents the circular rotatable table of the coiling machine, two of which are shown in connection with a surrounding platform a flush with the table 40 top, over which the coils may be delivered to a skid or other receiving device.

The coiling machine or machines are installed beyond the delivery end of a slat conveyor B adapted to receive the rolled strip through a suitable guide from the final pass of rolls C. In the event of additional reduction before reeling, the table B is arranged for lateral adjustment, as indicated in dotted lines to bring its receiving end in 45 line with a supplemental stand of rolls C', as will be readily understood. The strip c, as

delivered upon the conveyor from the mill, is not limited as to its speed of travel and may accumulate more or less, as indicated, being delivered edgewise through a pair of vertical guiding rollers b onto the conveyor where it may accumulate in looped formation, as shown, ready for being drawn therefrom by the coiling machine.

Immediately in advance of the coiling machine are a series of pivoted rollers d around which the strip is laced prior to being led onto the coiler, for exerting the necessary tension. The active elements of the machine are a series of annularly arranged fingers 2 55 which extend vertically through the central opening of rotatable table A between guiding lugs 2' thereof, preferably extending below its upper surface, which is smooth and unobstructed, when the fingers are lowered, 60 as in Fig. 5.

The fingers 2 are of any suitable number, as five, and are spaced apart by the intervening guides, between which they are freely movable, leaving ample space between any 75 two of the fingers for the insertion edgewise of the end of the strip c. Each finger extends by a projection 3 inwardly between upper and lower disks 4, 5, of an adjusting stem 6 by which the entire series are raised and 80 lowered through operating mechanism hereinafter described.

Fingers 2 are each connected with the table by a pair of links 7, 7, pivoted at 8 within sockets in their outer lower portion and at 9 85 to wings 10 of an annular hollow post 11 supporting the table by hub 12 on the upper end of main spindle 13. Hub 12 is keyed to the upper end of the spindle and further secured by a terminal nut 14, and bears by 90 washers 15 upon the upper end of the central standard frame 16 having suitable bushings at each end and an annular oil cup 17. A bevel gear 18 is keyed to spindle 13 and is in driving engagement with a bevel pinion 19 of shaft 20 mounted in bearings 21 of pedestal 16 and 22 of the base 23. A motor 24 is mounted on the base and coupled with shaft 20 at 25 for driving the table spindle at any desired speed.

95 Stem 6 extends downwardly through the center of spindle 13 and is connected with a

100

crosshead 26 which is pivotally connected at 27 between the bifurcated terminals of a lever 28 of rock shaft 29. A counterweight 30 is mounted on an arm 31 also keyed on shaft 29, as a counter-balance, and a lever 32 of the rock shaft is connected by rod 33 with the operating lever 34. Said lever is secured to a rock shaft 36 mounted in brackets depending below the operator's platform *aa* 10 which is preferably at a slightly higher level than that of table A, and the rock shaft has an operating handle lever 37 extending upwardly therefrom.

In operation, the end of strip *c* is inserted 15 between two of fingers 2 and bent around in hook form, the fingers being elevated. The fingers together constitute a skeleton core of annular shape around which the strip will be wound upon rotation of the table, gradu- 20 ally increasing in diameter until the entire rolled length has been coiled. Suitable outer guards 38 may be utilized, if desired, preferably removable, to retain the outer free end of the coil, which may be tied around 25 or otherwise secured, if desired, before removal. After being coiled and the machine being stopped, the fingers 2 are lowered to or below the level of the table A, as in Fig. 5, by operation of lever 37, when the coil 30 may be slid across the table and its surrounding platform for delivery, when the machine is ready for another operation upon again erecting fingers 2.

In either raising or lowering the fingers 35 2 recede towards the center, due to the toggle action of links 7 on their pivotal bearings 9, being correspondingly extended radially at their upper or lower positions.

As shown in Fig. 1, two of the coiling 40 machines are arranged side by side and may be used alternately, thereby affording continuous capacity for the strip as delivered from the mill. The machine as a whole is very compact, simple, and strong, and well 45 adapted to its intended use. It overcomes the objection of lifting or prying off the coil from a vertically immovable core, greatly reduces the time of the complete operation, and also overcomes the objection of all ob- 50 structing mechanism above the table.

It may be changed or varied in construction or different details by the skilled 55 mechanic, but all such changes are to be understood as within the scope of the following claims.

What I claim is:

1. A coiling machine having a vertically 60 movable laterally adjustable series of fingers forming a grasping, winding and re- leasing core, and means effecting inward lateral movement of the fingers simultaneous with their downward vertical movement.

2. A coiling machine having a vertically 65 movable laterally adjustable series of fingers forming a grasping, winding and re-

leasing core, and means for actuating them embodying controlling links for effecting inward lateral movement of the fingers simultaneous with their downward vertical movement. 70

3. A coiling machine having a vertically stationary rotatable table and a grasping, winding and releasing core consisting of an annular series of vertically movable laterally adjustable fingers extending therethrough and means effecting inward lateral movement of the fingers while maintaining their erect position and while effecting simultaneous downward movement thereof. 75

4. In a coiling machine, a supporting 80 standard, a rotatable spindle therein having an upper table, a series of vertically and inwardly movable fingers forming a circular winding core extending upwardly through the center of the table, means for lowering the fingers simultaneously with their inward movement, and for raising them. 85

5. In a coiling machine, a supporting 90 standard, a rotatable spindle therein having an upper table, a series of vertically and inwardly movable fingers forming a circular winding core extending upwardly through the center of the table, and a stem engaging the fingers having means for lowering them simultaneously with their inward movement, 95 and for raising them.

6. In a coiling machine, a supporting 100 standard, a rotatable spindle therein having an upper table, a series of vertically and inwardly movable fingers forming a circular winding core extending upwardly through the center of the table provided with inwardly extending lugs and outer pivoting links, and a vertically movable stem extending upwardly through the table spindle provided with abutments embracing the lugs for imparting inward lateral movement of the fingers simultaneous with their downward vertical movement. 105

7. In a coiling machine, the combination 110 with a centrally apertured table, of an annular series of expanding and contracting fingers extending therethrough, means for erecting them above the level of the table, and for lowering them by downward vertical movement simultaneous with their inward lateral movement. 115

8. A coiling machine provided with a rotatable table, a series of annularly arranged coiling fingers extending upwardly therethrough, and means for erecting and laterally expanding the fingers above the table and for lowering and laterally contracting them below its surface. 120

9. A coiling machine provided with a rotatable table, a series of annularly arranged coiling fingers extending upwardly therethrough, means for erecting the fingers above the table and for lowering them below its surface, and means for simultane- 125 130

ously imparting inward radial movement to the fingers.

10. A coiling machine provided with a rotatable table having a vertically movable series of spaced fingers extending through the table, a central raising and lowering spindle engaging the fingers, and toggle

actuating mechanism for imparting radial movement to the fingers, whereby they are contracted to release a coil in lowering to 10 the level of the table.

In testimony whereof I hereunto affix my signature.

HOWARD H. TALBOT.
